AIRPLANE CONSTRUCTION SET

William Robert Stockham, Jr., Burbank, Calif.

Application March 7, 1940, Serial No. 322,816

3 Claims. (Cl. 46—17)

This invention relates to toy airplanes, the general object of the invention being to provide sets of a plurality of parts each so that a child or other person can construct various types of airplanes with similar types having different arrangement of parts, thus amusing the child and making him familiar with the different parts of an airplane and of the different types of airplanes.

10 This invention also consists in certain other features of construction and in the combination and arrangement of the several parts to be hereinafter fully described, illustrated in the accompanying drawings and specifically pointed out in 15 the appended claims.

In describing the invention in detail, reference will be had to the accompanying drawings wherein like characters denote like or corresponding parts throughout the several views, and in which:

20 Figure 1 is an elevational view with parts broken away of an airliner type of plane.

Figure 2 is a top plan view of Figure 1.

Figure 3 is a front view thereof.

Figure 4 is a section on the line 4—4 of Figure 2.

Figure 5 is a front view but showing a different arrangement of the parts.

Figure 6 is an elevational view of a small cabin ship.

30 Figure 7 is a top plan view of Figure 6.

Figure 8 is a fragmentary front view of Figure 7.

Figure 9 is a view similar to Figure 8 but showing a slightly different arrangement of the parts.

35 Figure 10 is a view of an open cabin type of ship.

Figure 11 is a top plan view of Figure 10.

Figure 12 is a fragmentary front view thereof.

40 Figure 13 is a view similar to Figure 12 but showing a different arrangement of the wheels.

Figure 14 is a view of a single wheel assembly.

Figure 15 is a view of a double wheel assembly.

In describing the invention reference will be had to a set of eighteen pieces and wherein some of the parts are used in building the different types of ships but it is to be understood that duplicates of these parts may be provided in larger sets, if desired.

50 In a set of eighteen pieces there is one tail member 1 which is of tubular construction and tapers from its front end to its rear end and at the rear end it is provided with the usual rudders, elevators and stabilizers shown generally at 2 and it is also provided with the curved ground 55 engaging member 3. This tall member has its

front end adapted to be inserted in either the airliner body A, the small cabin body B or the open type body C as shown in Figures 1, 6 and 10, and the body is attached to the tail member by screws 4, the parts being formed of any suitable material such as tin and, of course, the parts are painted and otherwise marked to represent windows, doors and the like.

The set also includes one central wing section 5 which is of hollow construction and of substantially rectangular shape and has a semi-circular recess 6 in one face thereof which is shaped to receive a portion of anyone of the three bodies A, B and C and either to receive the lower part of the body as shown, for example, in Figure 4 15 or the top part of the body as shown in Figure 5. Long bolts 7 pass through the body and the winged section to fasten the two parts together as shown more particularly in Figure 4. There are two outer wing sections 8 of hollow construction and having their inner ends shaped to fit in the ends of the center section 5 and to be secured therein by the bolts or screws 9.

The set also includes four engine and propeller assemblies 10 each of which has its body of forked construction to fit over the front edge of a wing section 8 and to be fastened thereto by the screws or bolts 11, four of these assemblies being used with the wing structure of the body A or if desired but a pair of these engines may be used. 30 Each wing part 8 is formed with two pairs of holes 12 for receiving the screws 11.

Also the set includes a pair of single wheel assemblies 13 and a double wheel assembly as shown in Figures 14 and 15, the assemblies 13 including a forked bracket 13' having a shaft passing through the prongs thereof for holding the wheel 13'' with the bracket having a flat extension 15 which is adapted to be connected by screws or bolts to the part to which it is to be connected. The assembly 14 is made somewhat similar to that shown at 13 excepting that the bracket 14' is made large enough to support a long shaft 14'' which has the wheels 16 at its ends with the flat part 17 having holes therein for receiving bolts or screws to fasten the member to the part of the plane to which it is to be connected.

In the airliner type a pair of the single wheel assemblies may be attached to the inner motor assemblies by screws or bolts as shown in Figures 50 1 and 3 but if the wing is to be placed on the top of the body as shown in Figure 5 then both of the wheel assemblies 13 and 14 may be used, one connected to the bottom of the nose of the ship by screws or bolts passing into the holes 20, 55

shown in Figure 1 and the double assembly connected to the body of the ship as shown in Figure 5. This arrangement is also shown in Figure 10 where the motor assemblies 18 are omitted from the open type of body and the propeller 21 is connected to the nose of the ship. However, in this type of ship two of the assemblies 18 can be used and attached to the center wing section as shown in Figure 13.

10 Thus it will be seen that I have provided an inexpensive set of airplane parts which will permit a child or other person to construct various types and models of airplanes and to change the location of the parts on each type.

15 It is thought from the foregoing description that the advantages and novel features of the invention will be readily apparent.

It is to be understood that changes may be made in the construction and in the combination 20 and arrangement of the several parts provided that such changes fall within the scope of the appended claims.

Having described the invention, what is claimed as new is:

25 1. A combination set of toy airplane parts comprising a plurality of elongated tubular body parts representing the fuselages of different types of planes, an elongated and rearwardly tapered tubular part representing the rear part of a fuselage, a rudder and elevators at the rear end of the last-mentioned part, the front end of the last-mentioned part adapted to fit in the rear end of any one of the body parts, screws for holding the two parts together, a central wing section 30 of elongated form and of hollow construction with its ends open, bolts for connecting the central part of said wing section to any one of the body parts, a pair of outer wing sections having their inner ends fitting in the ends of the central section, fastening means for detachably connecting the outer sections with the ends of the central section, wheel assemblies, fastening means for detachably connecting the wheel assemblies to different parts of the plane, said parts having 35 holes therein for receiving the fastening means, motor and propeller assemblies and fastening means for detachably connecting said motor and propeller assemblies to parts of the plane.

2. A combination set of toy airplane parts comprising a plurality of elongated tubular body parts representing the fuselages of different types of planes, an elongated and rearwardly tapered tubular part representing the rear part of a fuselage, a rudder and elevators at the rear end of the last-mentioned part, the front end of the last-mentioned part adapted to fit in the rear end

of any one of the body parts, screws for holding the two parts together, a central wing section of elongated form and of hollow construction with its ends open, bolts for connecting the central part of said wing section to any one of the body parts, a pair of outer wing sections having their inner ends fitting in the ends of the central section, fastening means for detachably connecting the outer sections with the ends of the central section, wheel assemblies, fastening means for detachably connecting the wheel assemblies to different parts of the plane, said parts having holes therein for receiving the fastening means, motor and propeller assemblies and fastening means for detachably connecting said motor and propeller assemblies to parts of the plane, each wheel assembly including a forked part having its limbs extending downwardly, a wheel carrying shaft supported by the lower ends of said limbs and a rearwardly extending horizontal part connected with the upper ends of the limbs and having holes therein for receiving the fastening means.

3. A combination set of toy airplane parts comprising a plurality of elongated tubular body parts representing the fuselages of different types of planes, an elongated and rearwardly tapered tubular part representing the rear part of a fuselage, a rudder and elevators at the rear end of the last-mentioned part, the front end of the last-mentioned part adapted to fit in the rear end of any one of the body parts, screws for holding the two parts together, a central wing section of elongated form and of hollow construction with its ends open, bolts for connecting the central part of said wing section to any one of the body parts, a pair of outer wing sections having their inner ends fitting in the ends of the central section, fastening means for detachably connecting the outer sections with the ends of the central section, wheel assemblies, fastening means for detachably connecting the wheel assemblies to different parts of the plane, said parts having holes therein for receiving the fastening means, motor and propeller assemblies and fastening means for detachably connecting said motor and propeller assemblies to parts of the plane, each motor and propeller assembly including a body part forked at its rear end for fitting over a wing section at the front edge thereof and the prongs of the forked part having vertical holes therein for receiving the fastening means and the outer wing sections having pairs of holes therein for receiving the fastening means which connect the motor assemblies with said wing sections.

55 WILLIAM ROBERT STOCKHAM, JR.
